MOUTH HYGIENE KIT

Joseph J. Engelbreit, Chicago, Ill.

Application February 23, 1940, Serial No. 320,490

4 Claims. (Cl. 132—84)

This invention relates to a kit for facilitating the keeping of the mouth of the user in a hygienic condition, the general object of the invention being to provide a brush and massage part and a tubular handle forming part for containing cleaning material with valve means for controlling the passage of the material from the tubular part and a cover member for the brush and massage part, whereby the device can be readily carried in the pocket, pocketbook or elsewhere so that it will be at hand when it is desired to clean the teeth or other parts of the mouth.

This invention also consists in certain other features of construction and in the combination and arrangement of the several parts to be hereinafter fully described, illustrated in the accompanying drawing, and specifically pointed out in the appended claims.

20 In describing the invention in detail, reference will be had to the accompanying drawing wherein like characters denote like or corresponding parts throughout the several views, and in which—

25 Figure 1 is a front view of the device with the cover thereon.

Figure 2 is a similar view with the cover removed.

Figure 3 is a side view with parts in section.

30 Figure 4 is a section on the line 4—4 of Figure 1. Figure 5 is a section on the line 5—5 of Figure 2. Figure 6 is a section on the line 6—6 of Figure 1.

In these views the numeral 1 indicates a tubular member which forms a handle for the device and 35 this member has one end open and this end is adapted to be closed by a threaded plug 2 having a knurled outer part whereby it can be easily threaded into the end of the tubular member or removed therefrom. The other end of the tubular member is flat and is provided with a stud 3 and a side portion of the member 1 adjacent this last-mentioned end is formed with a flat part having a hole 4 therein and a U-shaped enlargement 5 is formed on the flat part around the hole 45 with the side portions or limbs of the U-shaped part forming guiding channels 6 for a valve plate 7 which has an enlarged head part 8 which is provided with the flanges 9 at its side edges and at the rear of the head part, this head part 50 being of substantially T-shape in plan as shown in Figure 5.

An elongated brush back forming member 10 carries the bristles 11 and said member is formed with a right angularly extending base part 12 55 which is stepped on its top and which has a hole

13 in its bottom part for receiving the stud 3 of the member 1, the stud being cemented or otherwise attached to the walls of the hole to permanently connect the member 10 with the member 1. The front part of this base is formed with a T-shaped opening 14 therein for receiving the T-shaped head 8 of the valve plate 7 and the rear wall of the opening 14 is formed with a recess 15 of elongated form but which has its top terminating short of the top of the base 10 so that the recess is closed at all points excepting the front thereof which opens out into the slot 14. A projection 16 is formed on the inner face of the head 8 of the valve plate and is movably arranged in the recess 15 so that it is impossible to entirely withdraw the valve plate from the guiding means.

In assembling the parts the valve plate is dropped into position on the member 1 and then the brush member is placed on top of the member 1 with the hole 13 receiving the stud 3, after glue, cement or the like has been placed on the parts to firmly hold the stud in the hole. Of course, when this is done the recess 15 being open at the bottom will receive the projection 16 of the valve plate and then when the parts are permanently connected together the projection 16 will operate in the recess 15 to limit upward movement of the valve plate and prevent the valve plate from being entirely removed from the parts but will permit the valve plate to be moved by a finger tip upwardly to a sufficient extent to uncover the opening 4 so that some of the contents of the tubular member 1 can pass through the opening 4 into the hand of the user so it can be placed on the bristles or it can be delivered into a receptacle of any suitable form.

A cover member 17 is provided for the brush part, this member being preferably of octagon shape in cross section as shown in Figure 6 with its bottom open so that it can be passed over the brush member into engagement with the base 12 which is of a shape to snugly fit in the lower open end of the cover member and the front of the cover member is formed with a notch 18 to receive the top of the valve plate so that when the cover member is in place the valve plate is held in closed position and it cannot be open until the cover member is removed. The cover member is formed with the longitudinally extending slots 19 for admitting air to the bristles.

Thus it will be seen that I have provided a simple form of device for enabling the teeth, gums and interior of the mouth to be treated to promote hygiene of the mouth with the parts

so constructed and arranged that the device can be easily carried in the pocket or a pocketbook or the like so that it can be used whenever desired, particularly after eating.

5 It is thought from the foregoing description that the advantages and novel features of the invention will be readily apparent.

10 It is to be understood that changes may be made in the construction and in the combination and arrangement of the several parts provided that such changes fall within the scope of the appended claims.

Having described the invention, what is claimed as new is:

15 1. A device of the class described comprising a tubular handle part having one end open, a closure for said end, a bristle carrying member having a base at one end, means for connecting the base to the other end of the tubular part, 20 said tubular part adjacent the last-mentioned end having an outlet opening therein, a sliding valve plate for closing the opening, and a cover member for fitting over the bristle carrying member with its open end snugly engaging the base part and having a part thereof engaging the valve 25 plate for holding the same closed.

2. A device of the class described comprising a tubular handle part having one end open, a closure for said end, a bristle carrying member having a base at one end, means for connecting the base to the other end of the tubular part, 30 said tubular part adjacent the last-mentioned end having an outlet opening therein, a sliding valve plate for closing the opening, and a cover member for fitting over the bristle carrying member with its open end snugly engaging the base part and having a notch therein engaging the valve plate for holding the same closed, said base part having a recess therein and the valve plate 35 having a projection thereon engaging the recess for limiting sliding movement of the valve plate.

3. A device of the class described comprising a tubular handle member having one end open, a closure member for said end, the other end of the tubular member being flat and having a projection thereon and a side portion at the last-mentioned end of the tubular member having an 40

outlet opening therein and guideways on said side part one on each side of the opening, a valve plate engaging the guideways for closing the opening and said valve plate having a T-shaped head, a projection on the inner face of said head, 5 a bristle carrying member having a wide base provided with a hole in its bottom part for receiving the projection on the end of the tubular member, said projection being adapted to be permanently fastened in the opening, the front end 10 of the stepped base part having a T-shaped opening therein for slidably receiving the T-shaped head of the valve plate and the rear wall of said opening having a recess therein for receiving the projection of the valve plate for limiting sliding movement of the plate. 15

4. A device of the class described comprising a tubular handle member having one end open, a closure member for said end, the other end of the tubular member being flat and having a projection thereon and a side portion at the last-mentioned end of the tubular member having an outlet opening therein and guideways on said side part one on each side of the opening, a valve plate engaging the guideways for closing the opening and said valve plate having a T-shaped head, a projection on the inner face of said head, a bristle carrying member having a wide base provided with a hole in its bottom part for receiving the projection on the end of the tubular member, said projection being adapted to be permanently fastened in the opening, the front end 20 of the stepped base part having a T-shaped opening therein for slidably receiving the T-shaped head of the valve plate and the rear wall of said opening having a recess therein for receiving the projection on the valve plate for limiting sliding movement of the plate, and a cover having its sides and top closed and its bottom open, said cover fitting over the bristle carrying member and the bristles with its open end frictionally engaging the base part of the bristle carrying member and said cover having a notch 25 in its lower end for receiving part of the valve plate for holding the valve plate closed and said 30 cover member having slots therein. 35

JOSEPH J. ENGELBREIT.
